UNITED STATES PATENT OFFICE

2,627,591

MEANS AND METHOD OF ANTISTROBOSCOPIC ARC OPERATION

George S. Sperti, Burlington, Ky., assignor to
Institutum Divi Thomae Foundation, Cincinnati, Ohio, a corporation of Ohio

Application June 27, 1944, Serial No. 542,368

12 Claims. (Cl. 315—99)

1

My invention relates to the operation of enclosed arc devices, and in particular fluorescent lights. As is well known, in the operation of these lights a distinct stroboscopic effect is observed.

An object of this invention is the provision of means and a method of operation in which the stroboscopic effect is greatly cut down or substantially eliminated.

Another object of the invention is the operation of such devices at very much greater efficiencies than have hitherto been attainable.

Yet another object of the invention is the attainment of these advantages in the operation of light sources which, where desired, either may be of standard construction or if modified need be modified only in minor particulars, and, indeed, in the direction of simplification of construction.

These principal objects of the invention and others which will be set forth hereinafter, or will be apparent to one skilled in the art upon reading these specifications, I attain by those constructions and arrangements of parts and in those modes of operation of which I shall now describe certain exemplary embodiments. Reference is made to the drawings which form a part hereof and in which:

Figure 1 is a diagrammatic representation of a light source and circuits for high-voltage operation.

Figure 2 is a diagrammatic representation of a light source and circuits for three-phase operation.

Figure 3 is a diagrammatic representation of a light source and circuits for low voltage operation.

Figure 4 is a partial circuit diagram showing another mode of securing a shift in phase.

Briefly, in the practice of my invention, I have found that it is possible to provide an enclosed arc device having two pairs of electrodes and to maintain arc discharges between the pairs of electrodes, i. e., an arc discharge between an electrode of one pair and an electrode of the other, and another arc discharge between the other electrode of the first pair and the other electrode of the second pair, which arc discharges are out of phase with each other so as very greatly to minimize the stroboscopic effect. In its simplest form my enclosed arc structure is similar to that of the familiar fluorescent tube and comprises an elongated envelope having a pair of electrodes at each end, the envelope being evacuated and containing a small quantity of such a substance as mercury. The envelope may also if desired, contain a quantity of noble gas. While the utility

2

of my invention is not confined to fluorescent lights, such lights are a particular field of utility for it, in which another advantage of my invention is obtained. When a structure such as that mentioned above is energized in the way hereinafter set forth, two arc discharges are maintained therein; but the illumination given off by the fluorescent coating on the envelope is much more than twice the illumination obtainable with a single arc discharge.

While I do not wish to be bound by theory, I explain this surprising effect as due to the very much more continuous activation of the fluorescent coating. Fluorescent coatings are not particularly efficient in giving off visible light when activated by ultra violet radiations, and their efficiency is diminished when the activation is intermittent. When the activation becomes more nearly continuous, their efficiency is very greatly increased. Hence, by my invention with the form of fluorescent light mentioned above, I am able to secure much more than twice the illumination from a single light source without the expenditure of proportionate energy.

Moreover, I have found that with the type of light source to which I have referred, having a pair of electrodes at each end, I can maintain the two arc discharges between respective electrodes of each pair without interference and without such cross fire between electrodes of each pair, as will give rise to any appreciable energy loss.

In Figure 1, I have shown at 1, the envelope of a fluorescent tube which envelope will be coated within with a suitable fluorescent coating. At each end there is a press 2 or 3 through which pass leads terminating in electrodes 4 and 5 for the press 2, and 6 and 7 for the press 3.

The form of these electrodes is not a limitation on my invention, and they may take any convenient form, from bare wires to more elaborate structures. The arrangement shown in Figure 1 is intended for high-voltage operation; and while this is not in all instances necessary, I prefer to have the electrodes or portions thereof, coated with an electron emissive substance. The electrodes become heated during the operation of the light surface and an electron emissive coating assists in the maintenance of the arc discharges in spite of fluctuations of the line voltage.

The electrodes 5 and 7 are connected by leads 8 and 9 to a secondary 10 of a transformer of which the primary 11 is connected across power leads 12 and 13. The electrodes 4 and 6 are connected by leads 14 and 15 to a secondary 16 of a

transformer of which the primary 17 is connected across power leads 18 and 19. These power leads may, of course, be the same as the power leads 12 and 13; and the transformers, instead of being separate entities, may be combined in a single structure.

Means are, however, provided for applying to one electrode of each pair an energizing voltage which is out of phase with the energizing voltage applied to the other electrodes of each pair. I have shown in Figure 1 a capacity 20, connected in parallel with the secondary 16 for this purpose.

There are other ways of securing a shift in voltage phase. In Figure 4 I have shown a capacity 21, connected in series with the secondary 16. Rotary converters may also be employed for this purpose if desired.

In the operation of the arrangement of Figure 1 an arc is struck between electrodes 5 and 7, and another arc is struck between electrodes 4 and 6; but the latter arc is out of phase with the former. The degree of out-phasing may be considerably varied. The preferred condition is attained when the two arcs are 90° out of phase with each other, but lesser degrees of out-phasing are operative and will greatly cut down the stroboscopic effect as well as greatly increase the efficiency. In general, the out-phasing will be between say 60° and the ideal of 90°.

There is substantially no cross fire between electrodes 4 and 5 or between electrodes 6 and 7.

In Figure 2, I have shown a fluorescent light source 22, arranged for three-phase operation. This light source has at one end three electrodes 23, 24 and 25, and at the other end another three electrodes 26, 27 and 28. Electrodes 25 and 28 are shown connected by leads 29 and 30, to one of the secondaries 31 of a three-phase transformer. The electrodes 24 and 27 are shown connected by leads 32 and 33, to another secondary 34 of the transformer. The electrodes 23 and 26 are connected by leads 35 and 36 to a third secondary 37, of the transformer. The three primaries 38, 39 and 40 are connected together, and to power leads 41, 42 and 43 in the ordinary three-phase bridge construction. It will be noted that the three secondaries 31, 34 and 37 are not connected together as is usual in three-phase transformers, but are operated as separate secondaries. Three arcs are thus maintained, one between electrodes 23 and 26, and another between electrodes 24 and 27, and the third between electrodes 25 and 28. These arc discharges are substantially 60° out of phase with each other.

In Figure 3 I have indicated diagrammatically the standard fluorescent light source 44 having at one end electrodes 45 and 46, and at the other electrodes 47 and 48. The electrodes of each pair however, are connected together within the envelope by filaments indicated at 49 and 50. These filaments are coated with electron emissive substance; and the structure is one intended for low voltage operation. The filaments are initially heated and the main arc is struck when the atmosphere within the light source has become sufficiently ionized, whereupon the filaments are usually de-energized as understood in this art. I have shown electrodes 46 and 48 connected by leads 51 and 52 to a secondary 53 of a transformer of which the primary 54 is connected across power leads 55 and 56. The secondary 53 may have the phase of its delivered voltage controlled by a capacity 57. The electrodes 45 and 47 are shown connected by leads 58 and 59 to a double-pole, double-throw switch 60. When this switch

is in the position shown in solid lines, the short circuiting element 61 connects leads 58 and 59. This throws the filaments 49 and 50 in series into the circuit of the secondary 53. The filaments 5 are energized and operate to ionize the atmosphere within the envelope, ultimately permitting an arc discharge between electrodes 46 and 48. When this occurs the switch 60 may be thrown to the position shown in dotted lines, in which position leads 58a and 59a act along with leads 58 and 59 to connect electrodes 45 and 47 across the secondary 62 of a transformer, the primary 63 of which is connected across power leads 64 and 65. A second arc therefore, is struck between electrodes 45 and 47; and since the voltage delivered by secondaries 62 and 53 are out of phase, this second arc discharge will be out of phase with the first mentioned arc discharge within the envelope, and the objects of my invention are thus attained.

Again, the two transformers may be built together as a single unit and either secondary may be out-phased as respects the other. Other modes of operation including the use of chokes and out-phasing means; rotary converters and the like, may be employed, and will be within the skill of the worker in the art to apply in the light of the teachings herein. The switch 60 may be arranged for automatic operation, as by thermoelectric means or otherwise, as will be readily understood.

Modifications may be made in my invention without departing from the spirit of it.

Having thus described my invention in certain exemplary embodiments, what I claim as new and desire to secure by Letters Patent is:

1. In a structure for the purpose described, a single, elongated envelope, four electrodes in said envelope located in pairs adjacent the ends of said elongated envelope, circuit means for applying an arc discharge voltage to two of said electrodes, circuit means independent of the first mentioned circuit means for applying an arc discharge voltage to the other two of said electrodes, said circuit means each being connected to an electrode of each pair so that separate arc discharges occur in the direction of the length of said elongated envelope, and means for causing said two arc discharge voltages to be out of phase with each other by substantially 60° to substantially 90°, whereby to minimize stroboscopic effects.

2. In a structure for the purpose described, a single, elongated envelope, four electrodes in said envelope located in pairs adjacent the ends of said elongated envelope, circuit means for applying an arc discharge voltage to two of said electrodes, circuit means independent of the first mentioned circuit means for applying an arc discharge voltage to the other two of said electrodes, said circuit means each being connected to an electrode of each pair so that separate arc discharges occur in the direction of the length of said elongated envelope, and means for causing said two arc discharge voltages to be out of phase with each other by substantially 60° to substantially 90°, whereby to minimize stroboscopic effects, said envelope having a coating of fluorescent substance energized by irradiation from each arc discharge whereby the efficiency of light emission from said fluorescent coating is greatly improved.

3. In combination, an arc discharge device comprising a single elongated envelope having a pair of electrodes adjacent each end thereof,

means for applying an arc discharge voltage to an electrode of each pair, means independent of said first mentioned means for applying an arc discharge voltage to the other electrode of each pair, and means for causing said discharge voltages to be out of phase with each other.

4. In combination, an arc discharge device comprising a single elongated envelope having a pair of electrodes adjacent each end thereof, means for applying an arc discharge voltage to an electrode of each pair, means independent of said first mentioned means for applying an arc discharge voltage to the other electrode of each pair, and means for causing said discharge voltages to be out of phase with each other, said last mentioned means comprising a means including inductance and capacity for modifying the voltage phase of one of said voltage application means.

5. In combination, an arc discharge device comprising an envelope with a path of arc discharge therein, sets of electrodes at each end of said path, each such set comprising three electrodes, a three-phase transformer having primaries connected bridgewise to the power leads of a three-phase power system, said transformer having separate secondaries, each such secondary connected respectively to an electrode of each set, so that each set of electrodes comprises respective electrodes powered for arc discharge by arc discharge voltages substantially 60° out of phase with each other.

6. The structure claimed in claim 5 including a fluorescent coating on said envelope.

7. In combination, a light source comprising an elongated envelope, a pair of electrodes at each end of an arc discharge path within said envelope, a filament associated with electron-emissive substance connecting the electrodes of each pair, means for applying power for arc discharge to one electrode of each pair, means for connecting together the other electrodes of each pair, whereby to energize said filaments, and means for connecting said last mentioned electrodes to a source of arc discharge power, said sources of arc discharge power arranged independently of each other to apply voltages to said electrodes which are out of phase with each other.

8. A method of operating arc discharge devices to diminish stroboscopic effect, which method comprises providing an arc discharge device with an arc discharge path and a set of electrodes at each end of said path, and independently powering respective electrodes of each set so as to produce along said path at least two arc discharges which are out of phase with each other.

9. A method of operating arc discharge devices

to diminish stroboscopic effect, which method comprises providing an arc discharge device with an arc discharge path and a set of electrodes at each end of said path, and independently powering respective electrodes of each set so as to produce along said path at least two arc discharges which are out of phase with each other, and locating a fluorescent coating so as to be activated by all such arc discharges.

10. The method of claim 8, wherein three electrodes are provided in each set, and the electrodes of each set are respectively powered by voltages from a three-phase power supply, which voltages are substantially 60° out of phase with each other.

11. A method of operating fluorescent light sources having a plurality of electrodes at each end, which comprises powering the electrodes of such a fluorescent light source so as to produce therein separate arc discharges following substantially the same path and which are between substantially 60° and substantially 90° out of phase with each other, whereby to diminish the stroboscopic effect and to increase the efficiency of visual light emission by more nearly continuously activating the fluorescent means in said fluorescent light source.

12. A method of operating fluorescent light sources having an arc discharge path and a pair of electrodes connected by filaments at each end, which comprises first connecting together one electrode of each pair and powering the other electrode of each pair, whereby to energize said filaments, thereafter breaking the connection between said first mentioned electrodes and powering said first mentioned electrodes independently with a voltage which is out of phase with the voltage of the first mentioned powering step.
